Kevin Prince(57) **CLAIM**

We claim the ornamental design for a fishing light, as shown and described.

DESCRIPTION

FIG. 1 is a perspective view of a fishing light, showing our new design;

FIG. 2 is a top plan view thereof;

FIG. 3 is a bottom plan view thereof;

FIG. 4 is a left-side elevational view thereof;

FIG. 5 is a right-side elevational view thereof;

FIG. 6 is a front elevational view thereof; and,

FIG. 7 is a rear elevational view thereof.

The broken lines show portions of the article which form no part of the claimed design.
